UNITED STATES PATENT OFFICE.

FRANK H. HAMPTON, OF PULLMAN, ILLINOIS, ASSIGNOR TO JACKSON CUSHION EDGE COMPANY, OF JACKSON, MICHIGAN.

CUSHION EDGE.

958,115.

Specification of Letters Patent. Patented May 17, 1910.

Application filed August 24, 1908. Serial No. 449,996.

To all whom it may concern:

Be it known that I, FRANK H. HAMPTON, a citizen of the United States of America, and a resident of Pullman, county of Cook, 5 State of Illinois, have invented certain new and useful Improvements in Cushion Edges, of which the following is a specification.

The main objects of this invention are to provide an improved form of cushion edge 10 adapted to form a firm support for the edges of the cushioned surfaces of a spring cushion while at the same time being sufficiently flexible to yield differently at different points when the pressure thereon is un- 15 equally distributed; to provide an improved arrangement of the edge pad with respect to the spring structure; to provide an improved form of fastening clip for connecting the edge pad to the spring structure, 20 which clips may be fastened at either straight or curved edges of a cushion and may be made of either wire or flat material; to provide an edge pad and fastening means which require no special base to rest upon, 25 but may be fastened directly to the upper convolution of a coiled spring; and to provide an improved construction for cushion edge pads whereby the pad will return to its normal shape after distortion. These ob- 30 jects are accomplished by the device shown in the accompanying drawings, in which—

Figure 1 is a section, partly broken away, 35 of a spring cushion embodying this invention. Fig. 2 is a section taken on the line 2—2 of Fig. 1 and illustrating the edge pad securing means as viewed from the bottom, the edge pad being also partly broken away to show the jointed, resilient reinforcement of the core. Fig. 3 is a corresponding view 40 showing a modified form of the fastening clip and the means for securing it to the spring frame. Fig. 4 is a side elevation of the parts shown in Fig. 3, the edge pad and cushion being shown in section, and the line 3—3 indicating the plane from which 45 Fig. 3 is viewed. Fig. 5 is a sectional detail indicating the method of folding and sewing the sheet of canvas which forms the casing of the edge pad.

In the form shown in the drawings, the 50 edge pad consists of a casing 1, preferably of canvas, filled with a stuffing 2 of felt, sawdust, hair, or other yielding material. The casing is preferably formed by folding a 55 sheet of canvas upon itself at 3, as shown in

Fig. 5, and sewing the two parts together at 4 along a line parallel with the fold 3 and spaced therefrom a sufficient distance to provide an edge pad of the desired diameter when the same is stuffed. The sheet of canvas is of sufficient width to provide comparatively wide flaps 5 and 6.

The spring frame may be of any usual construction. In the form shown in Fig. 1, the frame comprises a plurality of coiled 60 springs 7 of the usual helicoidal shape mounted upon a base 8. The edge pad extends around the top of the spring frame and is fastened to each of the springs in the outer row by means of a clip 9. The clips 9 are secured to the upper convolution of the 65 corresponding springs and are also fastened to a border plate 10 which extends along the edge of the frame and is riveted to each of the clips 9, thus serving to bind together the 70 upper ends of the springs 7 and also to support the stuffing 11 of the cushion adjacent 75 to the edge pad.

The fastening clips, in the form in which they are shown in Figs. 1 and 2, consist of 80 single strips of sheet metal. Each strip is bent to form a part 12 which encircles the edge pad. At another place it is bent to form a hook 13, which engages the outer part of the upper convolution of the spring 85 and the inner end of the clip, and at its inner end it is split to form the narrow 90 tongues 14 which are wrapped around the wire of the upper convolution of the spring. The part 12 of the clip is of such length that its end 95 will engage the seam 4 of the casing and hold said seam at a position close to the top of the spring frame when the flap 5 is pulled tightly over the top of the edge pad and secured to the bottom frame 8.

In assembling a cushion of this form, the clips and border plate 10 are first fastened to the tops of the springs, the hooks 13 and tongues 14 being at this time closed around the wire of the springs so as to firmly hold 100 the clips and border plate in position, the parts 12, however, being left in an open position, as indicated by the dotted lines in Fig. 1, so as to permit the insertion of the edge pad. After the edge pad is inserted into 105 position, the parts 12 are bent down to the position shown by full lines by means of a suitable tool. The flap 6 is laid along the upper surface of the frame, and the flap 12 is drawn over the top of the edge pad and 110

tacked or otherwise secured to the bottom of the frame. After the padding 11 is placed in position, it is covered by a sheet of fabric 15 which is sewed to the flap 5 at 16. This 5 is covered by the outer covering of the cushion, not shown in the drawings.

In the modification shown in Figs. 3 and 4, the fastening clip 17 is formed of wire instead of sheet metal, and the hook-shaped 10 bends 18 serve to secure the border wire 19 to the upper convolutions of the spring. In this form the connection between the clip 17 and the spring is reinforced by a second clip 20, and the clip 20 is riveted to the border 15 plate 10 between the two parts of the clip 17. When the clip is formed of wire, it is preferably doubled, as shown, the middle part 21 of the wire being shaped so as to have a broad bearing along the seam of the pad, 20 (See Figs. 3 and 4.)

With the form of fastening means which is herein shown, the edge pad is securely held in position while being at the same time free to yield under unequally distributed 25 local pressure which deflects some of the springs 7 more than others. The edge pad is, however, so supported that it always returns to its normal position and maintains the shape of the cushion. As the clips are 30 widely spaced, the edge pad is free to bend between adjacent clips, and it may yield either horizontally or vertically.

In order to insure that the parts of the 35 pad always maintain perfect alignment with each other when not under strain, the core thereof is reinforced by a resilient inner core 22 of metal. This inner core preferably comprises a series of sections or links hinged together, the links being of such length and 40 being so placed that their joints 23 are adjacent to the clips 9. Thus the edge pad is free to yield with the cushion springs under local pressure, but always assumes its normal shape when the pressure is removed. 45 The links 22 are embedded in the pad material so that they do not come into direct contact with the casing of the pad. In the form shown, the links 22 are each formed from a single piece of resilient wire looped 50 at each end to engage the adjacent links.

What I claim as my invention and desire to secure by Letters Patent is:-

1. In a cushion, the combination of a 55 spring frame, an edge pad extending along the upper edge thereof and comprising a casing formed of flexible material and stuffed with padding material, and a fastening clip secured to said frame and having a part encircling said edge pad.

60 2. In a cushion, the combination of a 65 spring frame, an edge pad extending along the upper edge thereof and comprising a casing formed of flexible material and stuffed with padding material, and a series of fastening clips disposed along the edge

of said frame, being spaced apart and each having a part encircling said edge pad for retaining the same in position.

3. In a cushion, the combination of a 70 spring frame comprising a plurality of coiled springs arranged in a row along the edge of the frame; an edge pad extending along the edge of the frame above said row of springs; and a plurality of fastening 75 clips, each having a part encircling said edge pad and having another part spanning the upper convolutions of one of said springs and engaging opposite sides thereof for securing said clip against shifting with respect to such spring.

4. In a cushion, the combination of a 80 plurality of coiled springs arranged in a row along the edge of the cushion; an edge pad extending along the edge of the cushion above said row of springs; and a fastening 85 clip spanning the upper convolution of one of said springs and comprising a part adapted to engage the edge pad for securing the same in position, a hook-shaped part adapted to engage one side of said upper convolution, and means for securing said clip to the opposite side of said upper convolution.

5. In a cushion, the combination of a 90 wire spring structure; an edge pad extending along the edge of said structure; and a plurality of fastening clips, each comprising a piece of metal bent upon itself at one end to encircle said edge pad, being also bent to form a hook for engaging a part of the 100 frame adjacent to the pad, and being bent upon itself at its other end to engage a part of the frame distant from said pad.

6. In a cushion, the combination of a 105 spring frame comprising a plurality of coiled springs arranged in a row along the edge of the frame; an edge pad extending along the edge of the frame above said row of springs; a border plate adjacent to the edge of said frame; and a plurality of fastening 110 clips secured to said border plate and each having a part encircling said edge pad.

7. A cushion, comprising a spring frame, an edge pad extending along the edge of said frame and comprising a sheet of flexible 115 material folded upon itself and having the parts which are at opposite sides of the fold stitched together along a line substantially parallel with the fold and a considerable distance inward from the edges of said parts 120 to form a tubular casing with a pair of flaps disposed along one side of the same, a filling of stuffing material in said casing, and fastening means adapted to secure said edge pad to said frame and having parts encircling said edge pad and bearing against the same between one of the flaps and the pad so as to permit such flap to be pulled tightly over and around the edge pad without turning it in said clips.

8. In a cushion, the combination of a spring frame, an edge pad extending along the edge thereof, means securing said edge pad at intervals to said frame, and jointed reinforcing means extending along said edge pad adapted to yieldingly support the same intermediate of said securing means.
9. In a cushion, the combination of a spring frame, an edge pad extending along the edge thereof, means securing said edge pad at intervals to said frame, and jointed reinforcing means extending along the interior of said edge pad adapted to yieldingly support the same intermediate of said securing means.
10. In a cushion, the combination of a spring frame, an edge pad extending along the edge thereof, means securing said edge pad at intervals to said frame, and reinforcing means extending along the interior of said edge pad adapted to yieldingly support the same intermediate of said securing means, said reinforcing means comprising a series of sections individually spanning the spaces between the successive securing means and each adapted to yield independently of the others.
11. In a cushion, the combination of a spring frame comprising a series of coiled springs arranged in a row along the edge of said frame, an edge pad extending along the edge of said frame and above said springs, individual fastening clips secured to the upper convolution of each of said springs for retaining said edge pad in place, and a plurality of links formed of resilient material extending along said edge pad, the successive links being hinged together at points adjacent to said clips.
12. In a cushion, the combination of a spring frame comprising a series of coiled springs arranged in a row along the edge of said frame, an edge pad extending along the edge of said frame and above said springs, a plurality of fastening clips secured to the upper convolution of each of said springs for retaining said edge pad in place, links extending along the interior of said edge pad between successive clips, each link comprising a piece of resilient wire looped at its ends to engage the adjacent links, and the joints between links being located adjacent to said clips.
13. In a cushion, the combination of a spring frame comprising a plurality of coiled springs arranged in a row along the edge of the frame; an edge pad extending along the edge of the frame above said row of springs; and a plurality of fastening clips, each having a part engaging said edge pad and having another part spanning the upper convolutions of one of said springs and engaging opposite sides thereof for securing said clip against shifting with respect to such spring.

Signed at Chicago this 7th day of August 1908. 65
